UNITED STATES PATENT OFFICE.

HENRY J. BROWN, OF NEW YORK, N. Y.

PHONOGRAPH BOOTH.

1,407,322.

Specification of Letters Patent. Patented Feb. 21, 1922.

Application filed September 2, 1920. Serial No. 407,700.

To all whom it may concern:

Be it known that I, HENRY J. BROWN, a subject of the King of England, residing at New York, in the county of Bronx and State 5 of New York, have invented certain new and useful Improvements in Phonograph Booths, of which the following is a full, clear, and exact specification.

This invention relates to booths for the 10 accommodation of prospective purchasers of phonograph records while they are listening to the playing of the records desired.

It is the object of the invention to provide 15 a private booth or compartment for each person, and to arrange the phonograph so that it may receive attention from outside the booth. In this way any desired records may be demonstrated or played for the customer without the attendant entering the 20 booth. Moreover, a single attendant may care for several booths at the same time.

The invention also contemplates the fitting 25 of each booth with means of communication between the customer within the booth and attendant without, and means for delivering the desired records to the customer while he is in the booth, so that he can take them with him and pay for them at a suitable desk as he leaves. Other objects 30 will appear as the description proceeds.

The invention will be first hereinafter described in connection with the accompanying drawings, which constitute part of this 35 specification, and then more specifically defined in the claims at the end of the description.

In the accompanying drawings, wherein 40 similar reference characters are used to designate corresponding parts throughout the several views:—

Figure 1 is a front elevation of a group or battery of three booths built together, showing the door to one of the booths or compartments open and occupied by a customer.

Figure 2 is a perspective view of the rear and end portions of the same group of booths showing how the attendant may obtain access to the phonographs for the several booths, and

Figure 3 is a vertical section through one of the booths and its phonograph compartment to show the arrangement of the parts more clearly.

The booths may be constructed in groups 55 of any desired number, three being a convenient number to be looked after by one at-

tendant. The dimensions of each booth may vary according to conditions, but generally each booth may preferably be built to accommodate a single person and be about 60 6'x30"x36". Each booth 1 is provided with a sound proof door 2 preferably having glass panes 3.

Within each booth there is provided a seat 4, a desk or table 5, a list of records or 65 catalog 6 and a rack 7 for memorandum cards on which the customer may write the names of the records he wishes to purchase. Into the booth opens the amplifying chamber or horn 8 of the phonograph which is 70 arranged in a compartment 9 above the booth and to which access is had by means of a hinged cover 10 which may be raised when desired by an attendant when standing upon a platform 11 running along the back 75 of the several booths. When said cover 10 is raised, the attendant may change needles and records at will. The turn-table 12 is rotated in the usual manner by a spring motor indicated at 13 in Figure 3 and which 80 may be wound by a crank 14 projecting from the rear of the compartment 9 or otherwise. A rack 15 is preferably constructed above the phonograph compartments for holding records for use on the 85 machines. Said rack 15 also serves to screen the attendant on the platform 11 from the front of the booth.

Each booth is fitted with a speaking tube 16 extending up through the top into convenient reach of the attendant, so that the customer in the booth may call up the names of the records he wishes to have played. Each booth may also be fitted with a chute 17 leading from the top and adapted to deliver records, wrapped ready for taking away, to a wall pocket 18 at the side of the booth, as shown in Figure 3.

It will be noted that the construction of booths for the purpose mentioned according 100 to the plan illustrated herein will mean great economy in space and cost of help, as well as saving of time and greater convenience for the customers. As the customers will not be permitted to handle the records being played or wind the phonograph, there will be no danger of breakage due to their carelessness. If desired, an electric light 19 and fan 20 may be provided in each booth and means provided for lighting the 110 light and starting the fan when a customer enters the booth and closes the door, so that

the attendant may then call down through the speaking tube and inquire what records he desires to have played. The amplifying chamber or horn 8 may have a sound modifying shutter 21 as shown in Figure 3 and which may be adjusted by the customer to regulate the volume of sound according to his taste, by means of the knob 22.

Having thus described my invention, what I claim as new and desire to secure by Letters Patent of the United States is:—

1. The combination with a customer's booth, of a phonograph arranged in a separate compartment associated with said booth, the horn of said phonograph opening into said booth.

2. The combination with a customer's booth, of a phonograph arranged in a compartment above said booth and having its amplifying chamber opening into the booth.

3. The combination with a customer's booth, of a phonograph arranged in a separate compartment and having its amplifying chamber opening into said booth, and means of access to said phonograph from outside the booth.

4. The combination with a customer's booth, of a phonograph arranged in a separate compartment and having its amplifying chamber opening into said booth, and means for winding the phonograph and applying and removing records from the outside of the booth.

5. The combination with a customer's booth, of a phonograph arranged in a separate compartment and having its amplifying chamber opening into said booth, means of access to said phonograph from outside the booth, and means of communication between a customer in the booth and an attendant for the phonograph on the outside.

6. The combination with a customer's booth, of a phonograph arranged in a separate compartment and having its amplifying chamber opening into said booth, means of access to said phonograph from outside the booth, and means for delivering records from an attendant on the outside to a customer in the booth.

50 7. The combination with a customer's booth, of a phonograph arranged in a separate compartment and having its amplifying chamber opening into said booth, means of access to said phonograph from outside the booth, and a speaking tube extending from the interior of the booth to the outside thereof adjacent the point of access to the phonograph.

8. The combination with a customer's

booth, of a phonograph arranged in a separate compartment and having its amplifying chamber opening into said booth, means of access to said phonograph from outside the booth, and a chute for records leading from the outside adjacent the point of access to the phonograph to the interior of the booth.

9. The combination with a customer's booth, of a phonograph arranged in a separate compartment and having its amplifying chamber opening into said booth, a chute for records leading from the outside to the inside of the booth, and a pocket at the lower end of said chute for catching the records dropped through the chute.

20 10. The combination with a plurality of customer's booths, of phonographs arranged in compartments separate from the booths and having their amplifying chambers opening into said booths, and a platform running along all of said booths on the outside thereof for accommodating an attendant and permitting him to look after all of the phonographs.

11. The combination with a customer's booth, of a phonograph arranged in a separate compartment carried by the booth and having its amplifying chamber opening into said booth.

25 12. The combination with a customer's booth, of a phonograph arranged in a separate compartment and having its amplifying chamber opening into said booth, a platform for an attendant at the back of the booth, means of access to the phonograph compartment from said platform, and a rack for records arranged above the booth and serving to screen the attendant from the front of the booth.

30 13. The combination with a customer's booth, of a phonograph arranged in a separate compartment and having its amplifying chamber opening into said booth, and a sound modifying device in said amplifying chamber under control of the occupant of the booth.

35 14. The combination with a customer's booth, of a phonograph arranged in a separate compartment and having its amplifying chamber opening into said booth, a shutter in the lower end portion of said chamber, and a knob on the outside of said chamber in reach of the occupant of the booth for controlling said shutter.

In testimony whereof I have signed my name to this specification.

HENRY J. BROWN.
